CIGAR MAKING MACHINE

Constantin Friedrich Röber, Dresden, Germany,
assignor to "Universelle" Cigarettenmaschi-
nen-Fabrik J. C. Mueller & Co., Dresden, Ger-
many

Application June 13, 1936, Serial No. 85,138
In Germany June 15, 1935

11 Claims. (Cl. 131—39)

This invention relates to cigar making machines, and more particularly to that portion of the cigar making machine wherein the wrapper is placed about the filler.

5 An object of this invention is to provide a means which may be combined with a cigar making machine by which the wrapper is adhesively secured to the filler and held in contact with the filler a sufficient length of time for the adhesive to take hold.

10 Another object of this invention is to provide means for receiving the wrapped cigar from the cigar making machine while at the same time holding the tip of the cigar in a manner to prevent loosening of the wrapper, the holding means subsequently delivering the cigar to a conveyor by means of which the finished cigar may be transferred to the desired point for packing or the like.

15 A further object of this invention is to provide a device of this kind which is so constructed that the capacity of the cigar making machine is not affected thereby, and at the same time the tip of the cigar is given the desired treatment to insure the maintenance of the wrapper about the 20 filler.

25 With the foregoing and other objects in view, the invention will be more fully described herein-after, and will be more particularly pointed out in the claims appended hereto.

30 In the drawings, wherein like symbols refer to like or corresponding parts throughout the several views,

Figure 1 is a detail end elevation of a device constructed according to an embodiment of this 35 invention, showing the device in the act of receiving a cigar from the cigar making machine, with which this device is associated.

Figure 2 is a vertical section, partly in detail, taken on the line 2—2 of Fig. 1.

40 Figure 3 is a view similar to Fig. 1, but showing the device in the act of delivering a finished cigar to a carry-off conveyor.

Figure 4 is a detail end elevation, partly in section, of the holding means for the cigar, showing 45 the manner in which the holding means for the cigar is opened to receive the cigar.

Referring to the drawings, the numeral 1 designates a drum or rotatable member mounted on a shaft 3 carried by a pair of arms 4. The drum 1 is provided on the periphery thereof with a plurality of longitudinally extending and circumferentially spaced apart grooves or channels 2, which in the present instance are angular in transverse section. The arms or levers 4 are 50 connected together by means of a cross bar 5, and

the lower ends of the arms or levers 4 are pivotally mounted on a shaft 6 carried by a bearing 7.

The cigars are maintained within the grooves 2 by means of clamping members 8 carried by rock levers 9 which are mounted on shafts 10 5 carried by the drum 1. The clamping member 8 is constructed in the form of a relatively long plate which is shaped transversely similar to the outer surface of the cigar. A spring 11 disposed about the shaft 10 constantly urges the lever 9 10 with the plate or holding member 8 to operative position. As shown in Fig. 3 each lever is provided with a stop lug 9' which limits the inward movement of the lever 9 with respect to the adjacent groove 2.

15 When the cigars are placed into a groove 2, a cup-shaped member 12 is moved to a position where the tip of the cigar is received on the inside thereof. This cup 12 is mounted on an arm 13 which is fastened to a slideable rod 14 by means 20 of nuts 15 or like fastening devices. The rod 14 is slideable in a passage 16 provided in the drum 1, and this rod 14 is held against rotation by means of a pin 17 which is secured thereto and which engages in a slot 18 in the drum 1. The length of 25 the slot 18 determines the movement of the rod 14. A spring 14' engages about the rod 14 and constantly urges the cup member 12 to an inoperative position, as shown in Fig. 2.

30 The cigars are received from the cigar making machine one at a time in a rockable receiving and delivering member 26 which is mounted on a shaft 27 carried by an arm 28 which is fastened to the frame of the machine. The rock member 26 is provided with a channel 25 in the upper 35 end thereof which is V-shaped, and this rock member is swung from a vertical receiving position, as shown in Fig. 3, to a substantially horizontal delivering position, as shown in Fig. 1 by means of a segmental toothed rack 30 carried by a 40 rock lever 31. The lever 31 is pivoted on a pivot 32, and the teeth of the rack 30 engage the teeth of a gear 29 which is mounted on the shaft 27. The lever 31 is provided intermediate the ends thereof with a roller 33 which engages in a cam groove 35 in a cam member 34. This cam member 34 is mounted on a drive shaft 24 connected to a suitable source of power supply.

45 When the combined receiving and delivering member 26 is rocked downwardly to a delivering 50 position under the rocking of the lever 31, the cigar Z is prevented from rolling out of the groove 25 by means of a pair of bars 52 which are secured to the carriage 26 as shown in Fig. 3. These bars 52 are provided with downwardly disposed 55

extensions 53, which are adapted, as shown in Fig. 4, to engage an edge of a clamping member 8 and thus swing the clamping member 8 into open position.

5 Figure 1 shows the device in a receiving position, with the carriage 26 delivering the cigar to the holding means. A spring 23 engaging a pin 22 carried by one of the levers 4 maintains the device in a receiving position. The levers 4 are 10 swung to a delivering position by means of a cam 20-21 mounted on a shaft 24. A roller 19 carried by one of the levers 4 engages the cam 20-21, and the spring 23 normally holds the roller 19 in 15 contacting relation with the cam 20-21.

15 After the cigar has been delivered to the drum 1, the cup member 12 associated with the channel 2 which has just received a cigar is moved inward to an operative position by means of a push-rod 41 which is slidably in a boss 40 carried by the frame G of the machine. The push-rod 41 has a block 42 secured thereto by means 20 of a set-screw 43 or the like, and this block 42 is provided with an annular groove 44. A roller 45 mounted on a lever 46 engages in the groove 25 44, and the lever 46 is rockably mounted on a pivot 47. A spring 49 engaging a pin 48 on the lever 46 maintains a roller 50 carried by the lever 46 into contact with a cam member 51 mounted 30 on the shaft 24. The inner end of the push-rod 30 41 is adapted to engage against the flat outer end 12' of a confronting cup member 12 and to hold this cup member 12 against the end of the cigar positioned in the groove 2.

A ratchet 38 is carried by one end of the drum 35 1, and a pawl 36 is mounted on the shaft 27, and held against the ratchet 38 by means of a spring 39. This pawl 36 is constructed in a hook-shape so that when the cam 20-21 swings the levers 4 to a delivering position, the pawl 36 will move the 40 drum 1 forward for the desired degree, and the cup member 12 which is held by the push-rod 41 will then move away from the rod 41 and will 45 slidably engage a segmental plate 54 which is fixed relative to the frame. This segmental plate 54 constitutes a holding plate for holding a number of the cup members 12 in operative position.

A pawl or clamp releasing arm 55 is mounted on a shaft 56 carried by a support 57, and this arm 55 is positioned in the path of the movement 50 of a lug 61 carried by the lever 9. A spring 59 which is connected at one end to a pin 58 mounted on the arm 55 and at the other end to a pin 60 constantly maintains the arm 55 in an operative position, as shown in Fig. 1. When the arm 55 55 engages the lug 61, and the drum 1 is rotated through one cycle by means of the pawl 36, the arm 55 will swing the clamping member 8 to a released position, as shown in Fig. 3, and the released cigar will then roll downwardly on an 60 inclined plate 62 onto a conveyor 63. At the time the lug 61 is initially engaged by the releasing arm 55, the drum 1 is rotated by the pawl 36, and the cup member 12 associated with the clamping member 8 which is being released will 65 pass the end of the segmental holding member 54, and the spring 14 will move the cup member 12 to a released position.

In the use and operation of this device, assuming that the device is in the position shown in 70 Fig. 3, where the carriage 26 is in a position to receive the cigar from the cigar machine. When the cigar Z has been received in the groove 25 of the carriage 26, the cam member 20-21 will act to effect movement of the drum 1 to the position 75 shown in Fig. 1, and at this time, the carriage 26

is swung downwardly, or to the right as shown in Figs. 1 and 3. The bar 53 will engage the clamping member 8, as shown in Fig. 4 and then swing this clamping member 8 to an open position. With the cigar Z in the receiving groove 2, 5 and with the associated clamping member 8 still held in open position by the bar 53, the push rod 41 will be moved inwardly through rotation of the cam 51 and the engagement of the roller 50 on the cam 51. Inward movement of the push rod 10 41 will move the confronting cup member 12 to an operative position about the end of the cigar, and when the levers 4 are swung outward under the action of the cam 20-21, the pawl 36 will 15 rotate the drum 1 sufficiently to bring the cup member 12 engaged with the push rod 41 into engagement with the segmental holding bar 54. The length of the bar 54 and the size of the drum 1 will determine the length of time that the cup member 12 will be held in operative position about 20 the end of the cigar.

Further rotation of the cam member 20-21 will effect outward swinging of the levers 4 and the drum 1 to the position shown in Fig. 3. As the levers 4 swing outwardly, the pawl 36 will 25 rotate the drum 1 through one cycle, and simultaneous with the outward swinging and the rotation of the drum 1, the releasing member 55 will contact with the lug 61 which is carried by the clamping member 8 disposed in the delivering position, so that the clamping member 8 which is in the delivering position will be moved to a released position, as shown in Fig. 3, and the cup member 12 will likewise be released from the holding bar 54 so that the cigar Z may roll down 30 the chute 62 onto the conveyor 63.

When the drum 1 swings to a delivery position, the carriage 26 is returned to a receiving position, and the upward swinging of the carriage 26 will permit the clamping member 8 held in 40 open position by the bar 53 to swing to a clamping position.

This device will hold the wrapper about the tip 45 end of the cigar until the adhesive used to hold the wrapped dries sufficiently to prevent un- 50 wrapping of the wrapper, and this device will perform this operation without in any way affecting the operation of the cigar making machine.

It is obvious that various changes and modifications may be made in the details of construction and design of the above specifically described embodiment of this invention without departing from the spirit thereof, such changes and modifications being restricted only by the scope 55 of the following claims.

What is claimed is:

1. In a cigar making machine, a movable carrier, means for delivering a cigar from the machine to the carrier, releasable clamping means 60 for holding the cigar on the carrier, means movable with the carrier for holding the wrapper at the tip end of the cigar, means for moving the carrier, and means for releasing a cigar from the carrier.

2. In a cigar making machine, a movable carrier, means for delivering a cigar from the machine to the carrier, releasable clamping means carried by said delivering means for moving said 70 clamping means to released position to receive a cigar, a cup-shaped member movable with the carrier and engageable with an end of the cigar to hold the wrapper against unwinding, yieldable means constantly urging said cup-shaped mem- 75

- ber to inoperative position, slidable means engageable with said cup-shaped member to move said cup-shaped member to operative position, a stationary member engageable with said cup-shaped member upon movement of the carrier to maintain the cup-shaped member in operative position, means for moving the carrier, and means active upon movement of the carrier in one direction for moving said clamping means to released position.
3. In a cigar making machine, a movable carrier, means for delivering a cigar from the machine to the carrier, releasable clamping means for holding the cigar on the carrier, means carried by the delivering means for moving said clamping means to released position to receive a cigar, a cup-shaped tip engaging member movable with the carrier, means for slidably mounting said tip engaging member on the carrier, yieldable means constantly urging said tip engaging member to inoperative position, means active upon delivery of a cigar to said clamping means for moving said tip engaging member to an operative position about the tip end of a cigar, means for holding said tip engaging member in operative position during the movement of the carrier from a receiving position to a delivering position, said holding means upon movement of the carrier to a delivering position permitting release of said tip engaging member, and means active upon movement of the carrier to delivering position to move said clamping means to released position.
4. In a cigar making machine, a movable member provided with cigar receiving means, means for delivering a cigar to said receiving means, means for moving said member, a stationary member associated with said movable member, a spring-pressed tip engaging member carried by said movable member, and means engageable with said tip engaging member to move said latter member into engagement with said stationary member to thereby engage the tip of the cigar.
5. In a cigar making machine, a movable member provided with cigar receiving means, means for delivering a cigar to said receiving means, clamping means carried by said movable member for holding a cigar in said receiving means, means carried by said delivering means for moving said clamping means to released position, means progressively moving said movable member, tip engaging means engageable with and disengageable from the tip of a cigar, and means disposed in the path of the movement of said clamping means to move said clamping means to released position.
6. In a cigar making machine, a movable member provided with cigar receiving means, a rockable cigar delivering member, operating means for said delivering member, clamping means carried by said movable member for holding a cigar in said receiving means, means carried by said delivering member engageable with said clamping means to move said clamping means to released position, resilient means engaging said clamping means to constantly urge said clamping means to clamping position, means progressively moving said movable member, tip engaging means engageable with and disengageable from the tip of a cigar, and a second releasing means disposed in the path of the

movement of said clamping means to move said clamping means to released position.

7. In a cigar making machine, a movable member provided with cigar receiving means, a rockable cigar delivering member, operating means for said delivering member, clamping means carried by said movable member for holding a cigar in said receiving means, means carried by said delivering member engageable with said clamping means upon rocking of said delivering member to delivering position for moving said clamping means to released position, means constantly urging said clamping means to clamping position, a second releasing means disposed in the path of the movement of said clamping means to move said clamping means to released position, a spring-pressed tip engaging member, means for moving said tip engaging member to an operative position, and means engageable with said tip engaging member for holding said member in operative position for a portion of the movement of said movable member.

8. In a cigar making machine, a movable carrier, means for delivering a cigar to the carrier, releasable clamping means for holding the cigar on the carrier, spring-pressed means movable with the carrier for holding the wrapper at the tip end of the cigar, means for moving the carrier, and means engageable with said clamping means for moving said clamping means to discharging position.

9. In a cigar making machine, a movable carrier, means for delivering a cigar to the carrier, releasable clamping means for holding the cigar on the carrier, means carried by said delivering means for moving said clamping means to released position during the delivery of a cigar to the carrier, means for moving the carrier, tip engaging means engageable with and disengageable from the tip of a cigar, and means engageable with said clamping means upon movement of said carrier to move said clamping means to released position to thereby discharge the cigar from the carrier.

10. In a cigar making machine, a movable carrier, means for delivering a cigar to the carrier, releasable clamping means for holding the cigar on the carrier, means carried by said delivering means for moving said clamping means to released position during the delivery of a cigar to the carrier, means for moving the carrier, a tip engaging member movable with said carrier, means active upon delivery of a cigar to said carrier for moving said tip engaging member to operative position, and means holding said tip engaging member in operative position for a portion of the movement of said carrier.

11. In a cigar making machine, a movable carrier, means for delivering a cigar to the carrier, releasable clamping means for holding the cigar on the carrier, spring-pressed means movable with the carrier for holding the wrapper at the tip end of the cigar, means engageable with said spring-pressed means for holding said spring-pressed means in operative position for a portion of the movement of said carrier, means for moving the carrier, and means for releasing a cigar from the carrier.
